REFRIGERATOR CAR CONSTRUCTION

Alfred G. Bancroft, Chicago, Ill., assignor to
 Standard Railway Devices Company, Chicago,
 Ill., a corporation of Delaware

Application September 10, 1941, Serial No. 410,243

3 Claims. (Cl. 62—17)

This invention relates to refrigerator cars used to transport perishable commodities at a predetermined temperature. The usual features of such a car are an insulated structure and a refrigerating means for use in warm weather and preferably a heating means for use in cold weather.

The invention relates particularly to refrigerator cars of the overhead bunker type. Cars of this type have the refrigerant containers disposed immediately below the roof and are commonly provided with drip pans below the containers to form refrigerant compartments below the roof and adjacent the side walls of the car. It is also common to provide vertical flues associated with the side walls and extending to near the floor. These flues serve as passages for the flow of refrigerated air from the refrigerant compartment to below the floor racks of the car so that such air may circulate upwardly through the lading. The flues also serve to drain off melted refrigerant when a foraminous or semi-foraminous container is used or to drain off condensation from the container when liquid retaining tanks are used. Such melted refrigerant further cools the circulating air by contact therewith and also contributes to the insulating qualities of the car walls.

Each side wall of a refrigerator car is preferably provided with a door through which lading is transported into the car. These doors must be large enough to permit passage of a truck therethrough and are usually about four feet wide. The refrigeration of the car is dependent upon cold air circulating downwardly through the above mentioned flues which are associated with the side walls of the car. To interrupt a flue for a distance of four feet would obviously lessen the refrigerating efficiency, particularly since the interruption would be at the doorway where more refrigeration is desirable to overcome the effect of insulation deficiencies at the door joints.

The problem of maintaining adequate refrigeration adjacent the doorway has been solved by providing ducts on the doors. When the doors are closed, the ducts are aligned with certain of the side wall flues to form continuous passages for the flow of air from the refrigerant compartment to the lower part of the car. In other words, the operation is as if the doors were non-existent.

The flow of liquid through the door ducts is undesirable for two reasons. In the first place when the doors are open, such liquid would fall

upon persons and lading entering or leaving the car with obvious disadvantageous results. In the second place, when the doors are closed, it is practically impossible to maintain a watertight relation between the aforesaid flues and ducts; the contents of the car are therefore liable to damage by such liquid.

My present invention pertains particularly to cars in which at least the lower parts of the refrigerant containers are imperforate so as to retain a quantity of liquid. A commonly used container of this type is substantially imperforate except for a few overflow apertures spaced above the bottom. The container is thus adapted to hold a limited quantity of a low temperature mixture of ice and brine which cools air coming in contact with the bottom of the container. Such air is further cooled by intimate contact with liquid which has escaped through the aforesaid apertures.

The object of my invention is to arrange the overflow means in such a way as to prevent the flow of liquid through the door ducts and to direct such liquid through the side wall flues, preferably adjacent the doorways. The means which I disclose for carrying out my invention direct the liquid into the desired paths without interfering with the circulation of cold air.

Other objects and advantages of my invention will be apparent from the following detailed description by referring to the accompanying drawings.

In the drawings:

Fig. 1 is a transverse section through a refrigerator car embodying my invention, the left side being on line 1L—1L of Fig. 2 and the right side on line 1R—1R of Fig. 2.

Fig. 2 is a section on line 2—2 of Fig. 1.

Fig. 3 is a section on line 3—3 of Fig. 2.

The general parts of the refrigerator car shown are insulated roof 2; side walls 3; floor 4; hatches 5; refrigerant containers 6; side wall flues 7; foraminous floor rack 8 and space 9 between rack 8 and floor 4. Refrigerant containers 6 are positioned directly below the roof 2 and preferably adjacent each side wall 3. Drip pans 12 are provided below the containers 6 and spaced apart partitions 14 are secured in upstanding positions at the edges of the drip pans 12. The drip pans 12 and partitions 14 cooperate with the roof 2 and side walls 3 to form enclosing structures 11 around the containers 6, air inlet openings 15 being provided by spacing the partitions 14 from the roof 2. Air discharge openings 17 which lead to the side wall flues are provided for flow of cold

air to such flues. Doorways are provided through the side walls 3 (see left side of Fig. 1) and a pair of doors 20 are adapted to close each doorway, the doors 20 having associated therewith ducts 21 are aligned with the flues 7a when the doors 20 are closed.

Air circulation is as follows: Air in the lading compartment 18 is warmed by contact with the lading and rises through the duct 16 between the partitions 14 to enter the enclosing structures 11 through the air inlet openings 15. The air is cooled by contact with the refrigerant containers 6 and falls by reason of its greater density through the discharge openings 17. Adjacent the doorways, the cold air flows through the door ducts 21 to the space 9. Remote from the doorway, the cold air flows through the flues 7 to the space 9. Such cold air then rises through the rack 8 to the lading compartment 18.

The refrigerant containers 6 disclosed are substantially imperforate except as hereinafter described and except for openings 24 in the tops 25 aligned with the hatches 5 for loading refrigerant into the containers. Inverted channel shaped baffles 27 reinforce the containers and retard the surging of refrigerant. Longitudinally extending angle members 28 secured to the sides of the containers 6 are supported at their opposite ends by carlines 30 which extend between and are secured to the side walls 3.

The containers 35 which are positioned adjacent the doorways are each provided with two groups 36 of overflow apertures 38 in the container walls 39 nearest the center of the car. One group 36 of apertures 38 is positioned near each of the end walls 41 of the container 35 in alignment with one of the flues 7. A hood-like structure 42 is provided for each group of apertures 38, which structure has a closed front 44, closed top 45, closed ends 47 and open bottom to direct to the drip pan 12 liquid which overflows through the apertures 38. The drip pan 12 is provided with upstanding ridges, such as the angles 48, which define channels for leading the overflowed liquid to the flues 7 and for preventing the entrance of the liquid into the flues 7a and ducts 21. The center parts of the containers 35 adjacent the doorways are imperforate. The apertures 38 may be provided adjacent either end but preferably adjacent both ends of each containers 35, as disclosed.

The accompanying drawings illustrate the preferred form of the invention, though it is to be

understood that the invention is not limited to the exact details of construction shown and described, as it is obvious that various modifications thereof, within the scope of the claims, will occur to persons skilled in the art.

I claim:

1. In a refrigerator car having a wall, a refrigerant container adjacent the upper part of said wall, a doorway through said wall below said container, flues associated with said wall adjacent each side of said doorway, means to overflow liquid from said container and a drip pan below said container to direct said liquid to said flues, said overflow means being disposed only in alignment with said flues and comprising apertures and a hood-like structure having closed front and closed ends attached to the exterior of said container in alignment with said apertures, said drip pan being provided with upstanding ridges spaced apart to form channels for flow of liquid from said overflow means to said flues.

2. In a refrigerator car having a wall, a refrigerant container adjacent the upper part of the wall, a doorway through the wall below the container, a flue associated with said wall adjacent at least one side of said doorway, a drip pan spaced below said container to form a passage arranged to communicate with the upper part of said flue, and ridges on the upper side of said drip pan spaced apart to form a channel leading to said flue, said container being substantially devoid of overflow means except for apertures aligned vertically with said channel for overflow of liquid from said container into the channel and thence into said flue.

3. In a refrigerator car having a wall, a refrigerant container adjacent the upper part of the wall, a doorway through the wall below the container, a flue associated with said wall adjacent at least one side of said doorway, a drip pan spaced below said container to form a passage arranged to communicate with the upper part of said flue, ridges on the upper side of said drip pan spaced apart to form a channel leading to said flue, said container being substantially devoid of overflow means except for apertures aligned vertically with said channel, a hood-like structure attached to the exterior of said container in alignment with said apertures and having an open lower side facing said channel to direct overflowed liquid into the channel and thence into said flue.

ALFRED G. BANCROFT.
